UNITED STATES PATENT OFFICE

164,430

ORDER HOLDING ATTACHMENT FOR BOTTLES

Gordon H. Lawhorn, Ellerson, Va.

Application April 13, 1951, Serial No. 14,818

Term of patent 3½ years

(Cl. D58—26)

To all whom it may concern:

Be it known that I, Gordon H. Lawhorn, a citizen of the United States, residing at Ellerson, in the county of Hanover and State of Virginia, have invented a new, original, and ornamental Design for an Order Holding Attachment for Bottles, of which the following is a specification, reference being had to the accompanying drawing, forming part thereof.

The dominant features of my design reside in the portions shown in full lines.

I claim:

The ornamental design for an order holding attachment for bottles, as shown and described.

GORDON H. LAWHORN.
